PAPER LID

Russell H. Anderson, White Plains, and John P. Campagnelli, Bethpage, N.Y., assignors, by mesne assignments, to Haskon, Inc., Mountainside, N.J., a corporation of Delaware

Filed Mar. 7, 1963, Ser. No. 263,483
1 Claim. (Cl. 229—43)

This invention relates to paper lids for food packages or the like.

Another object is to provide a lid of the above type having novel and improved characteristics.

Another object is to provide a lid adapted to snap into a cup groove and to grip the rim of the cup.

Another object is to provide a paper lid of the above type having means to prevent the outer skirt from absorbing moisture and becoming deformed while on the container.

Various other objects and advantages will be apparent as the nature of the invention is more fully disclosed.

The invention will be better understood from the following description, taken in connection with the accompanying drawings in which a specific embodiment has been shown for purposes of illustration.

In the drawings:

FIG. 1 is a transverse section through a lid and before the liner has been inserted and locked in place;

FIG. 2 is a similar section showing the finished lid with the liner locked in place and with the outer bead for snapping into a cup groove;

FIG. 3 is a partial transverse section through the lid and die at the beginning of the bead forming operation;

FIG. 4 is a similar broken longitudinal section through the lid and die at the completion of the bead forming operation;

FIG. 5 is a partial view of the lower die member;

FIG. 6 is a broken elevation, partly in section, illustrating the lid in place in a cup.

FIG. 7 is a detail view illustrating the skirt forming portion of the lid forming die; and

FIG. 8 is a detail showing the nesting position of a pair of stacked lids.

Referring to the drawing more in detail the invention is shown as applied to a lid for a food container of the paper cup type. This lid comprises a lower diaphragm 1 adapted to close the cup or the like and an upstanding rim housing having a vertical inner peripheral wall 2 terminating in an outwardly flared wall 3, a downwardly inclined top wall 4 and an outer skirt 5 having a compacted and thickened lower flange 6.

The lid above described is preferably made from wax treated, non-absorbent paper, or the like in a forming die of the type shown in Goodwin et al, Patent No. 2,447,855, dated August 24, 1948. The die includes a plurality of concentric rings adapted to form the inner diaphragm and the walls of the rim housing. Generally the upper die member includes a central plunger 80, adapted to form the lid diaphragm 1, a ring 75 having a cylindrical surface 75a and a tapered portion 75b adapted to form the inner housing walls 2 and 3 respectively, and an outer ring member 110 having an inclined top surface 110a to form the top wall 4 of the lid and a cylindrical skirt-forming surface 110b having an annular recess 110c to form the outer skirt 5 and thickened flange 6 of the lid.

The lower die member includes a central plunger 164 having an upper surface 175, a ring member 164 having surfaces conforming to the lid walls 2, 3, 4 and 5, and an outer forming ring 150 adapted to engage the bottom of the skirt flange 6 to compact the flange within the recess 110c. The die elements above described corre-

2

spond substantially to similarly numbered elements in said Goodwin et al. patent.

The lid above described is preferably made from a wax treated non-absorbent paper or the like.

5 The disc 10 of non-absorbent material such as waxed paper is disposed over the diaphragm 1 of the lid and is locked in place in a groove 44 formed by the bead 43 in the inner surface of the wall 2 of the rim housing.

The disc 10 is applied to the top of the diaphragm and 10 the lid placed in a die as shown in FIGS. 3 and 4. This die comprises a base 15 carrying a lower plunger 16 having a top diaphragm 17 on which the lid is seated and a downwardly extending peripheral skirt 18. The plunger is held in its upper position by a coiled spring 19.

15 A plurality of die segments 20 are mounted to slide radially between a lower ring 21 and an upper ring 22 which are secured together in spaced relationship by spacing posts 23. The lower ring 21 is formed with radial grooves 24 in which beads 25 on the segments 20 slide 20 radially for guiding and positioning the segments.

The rings 21 and 22 are biased upwardly by springs 26 only one of which is shown and are adapted to be depressed by a shoulder 27 on the skirt 18 of the plunger 16.

25 Each segment is provided with ears 30 to which a link 31 is pivoted. The links 31 are pivoted to ears 32 formed on a fixed ring 33. Stop posts 36 carried by the ring 33 limit the upward movement of the rings 21 and 22.

The segments 20 are formed with conical arcuate surfaces 40 adapted to compress the outer surface of the wall 2 of the lid and with a peripheral groove 41 adapted to form an outer bead 43 on the wall 2. The wall is thus folded over the edge of the disc 10 to form an internal groove 44 in the wall 2 opposite the bead 43. The disc 10 is thus seated in the groove 44 and is locked in place thereby.

It will be noted that the outer diameter of the bead 43 corresponds to the outer diameter of the wall 2 before compressing and that the wall 2 is tapered inwardly from its upper edge to the top of the bead 43 as a result of the compressing or forming operation.

The die includes an upper plunger in the form of a metal disc 45 carried by a rod 46 and adapted to rest upon the disc 10 of the lid.

45 In the forming operation the lid with its disc is placed on the lower plunger 16 and the upper plunger 45 is brought down upon the disc 10 of the lid. The disc 10 and lid are then further depressed with the lowering of the plunger 16 until the shoulder 27 of the plunger engages the ring 21. At this point the light diaphragm has been brought downwardly into alignment with the bead forming grooves 41 on the segments 20. Further depression of the upper plunger 45, lid and lower plunger 16 compresses the springs 26 and depresses the rings 21 and 22 to the position shown in FIG. 4. This depression of the latter rings causes the links 31 to push the segments 20 inwardly to compress the wall 2 of the lid around the edge of the disc 10 to form the inner groove 44 and outer bead 43 on the wall 2. The outer bead 43 is adapted to fit into an internal groove 47 in the wall of the cup 48 while the outer skirt 5 extends over rim 49 of the cup as shown in FIG. 6.

55 A lid of the above type is particularly adapted for use with paper cups in which refrigerator foods and products are dispensed. It may be used, however, with other containers having an appropriate upper rim and internal groove to receive the rim housing and the external bead 43 respectively of the lid. The shape and form of the lid may of course be varied in accordance with the particular container to which it is to be applied.

60 In this embodiment the lower flange 6 of the lid skirt 5 is considerably thicker than the remainder of the skirt and

is highly compacted. The highly compacted state materially reduces the tendency of the skirt to absorb moisture which would result in a softening of the skirt structure. The increased thickness and hardness prevent the skirt from flaring outwardly and producing an unsightly package, while, for example, the container is in the refrigerated compartment of a store.

The flared wall 3 is disposed at an angle such that the outer bead of a nested lid rests within the wall 3 of the lid below without being bound therein. When a lid is fed from the stack as shown in FIG. 8 the bead of the top lid is cammed up by the inclined wall 3 of the lid below until the top lid rides over the rim housing of the lower lid and slides off the stack without bending.

What is claimed is:

A paper lid for food containers or the like composed of wax paper and comprising a central diaphragm adapted to form a closure for the container and an integrally formed rim housing having an inner peripheral wall formed with a lower substantially vertical portion and with an upper flared portion adapted to receive the bottom of a nested lid, a top wall, an outer depending skirt, said

5 skirt terminating at its lower end in a compacted flange having a greater thickness than the remainder of the skirt, an external peripheral bead formed on the lower portion of said inner peripheral wall with said bead being adapted to rest on the flared upper portion of the peripheral wall of a nested lid and being adapted to fit into the corresponding internal groove of a container, an internal groove formed in the inner surface of said peripheral wall in alignment with said external bead, and a reinforcing disc 10 seated in said groove prior to closing of a container by the lid.
